MUFFLER FOR INTERNAL COMBUSTION ENGINES

Ambrose J. McNamara, Utica, N. Y.

Application January 18, 1928, Serial No. 247,558

4 Claims. (CL 181—57)

This invention relates to an improvement in mufflers for quieting and muffling the exhaust gases from internal combustion engines.

Mufflers for deadening or muffling explosive noise of an internal combustion engine are commonly used, especially on automotive vehicles. Common muffler construction consists of a shell arrangement or an assembly of interfitting cups having a plurality of baffles inside which are arranged to more or less tear up the exhaust gases that pass tortuously through the muffler before reaching the atmosphere. Much of the time the exhaust gases which reach the muffler are not fully burned and final burning takes place in the muffler. It is well known that the use of a muffler creates a back pressure of the exhaust gases upon the engine, due to the fact that the flow of the exhaust gases is interfered with, thereby reducing the efficiency of the engine.

The present invention aims to provide a muffler which will reduce to a minimum the back pressure upon an engine, and which is constructed so that a charge or body of exhaust gas which may not be completely burned, is torn up in such a manner as to cause the interior portion of this body of exhaust gas to be brought to the interior portions of the muffler shell. Accordingly, one or more muffling devices are provided within the muffler arranged, in a way, to obstruct the passage of the exterior layers of a body of discharged gas but which permits the more central layers, or the heart of the body of gas, to pass on through the devices substantially unobstructed. Where a plurality of such devices are used they are so arranged to successively remove outside layers of a body of gas until the inside of the body of gas itself may be deflected adjacent the interior walls of the muffler where its heat is dissipated.

Other objects and advantages of the invention residing in the combination of the elements, arrangements of the parts, and in the details of construction, will be evident during the course of the description hereinafter, wherein the terms used are merely descriptive. It will be apparent that there are numerous ways in which a muffler embodying the present invention may be designed other than those shown herein.

In the figures of the accompanying drawings which form a part of this specification, and wherein like numerals are employed to designate corresponding and like parts throughout the same,

Figure 1 is a central longitudinal sectional view 55 of a cup muffler embodying a preferred form of

the invention, parts thereof being shown fragmental.

Figure 2 is a transverse sectional view on lines 2—2 of Figure 1.

Figure 3 is a partial central longitudinal sectional view showing a modified arrangement of the baffles of the muffler shown in Figure 1.

Figure 4 is a central longitudinal sectional view of a shell type muffler embodying a modified form of the invention, and,

Figures 5 and 6 are transverse sectional views taken on corresponding lines of Figure 4.

The muffler shown in Fig. 1 consists of a multiplicity of interfitting cup members, which when interfitted together form a muffler shell, generally referenced 1. These cups may be clamped together by suitable bolts 2 which extend through the muffler with nuts on either end thereof. The exhaust inlet for the muffler is shown at 3, the outlet at 4. End plates 5 and 6 are provided for closing the ends of the muffler shell.

This muffler may be made of several types of cup members as shown in the present form. The cup members 7 are provided with relatively small inwardly extending flanges 8 to give the cups sufficient rigidity and strength but which permit exhaust gases to pass through. These cup members 7 act as spacers for cup members 9 that are provided with relatively deep flanges 10. These inwardly extending annular flanges 10 are provided with a central opening, into which is fixed a tapering tubular member 11. These members 11 are in the nature of reversed megaphones and have the large end 12, thereof, pointed towards the oncoming gases. Preferably, these conical passageways 11 are circular in cross section but it is within the invention to make them any other shape in cross section.

Cup member 15, having a plurality of apertures 16 formed in the transverse bottom portion 14 thereof, is disposed immediately to the rear of the last spacer cup 7, and a diffusing cone 17, as shown, if desired, may be formed in the bottom portion 14 of cup 15. The rear of the muffler is made up of the similar cup members 18, as shown, and a final cup 19 is used to complete the assembly. The cups 18 have an opening 22, formed centrally in the bottom flanges 20 thereof, through which the re-entrant pipe 23 extends inwardly of the muffler to provide a chamber 21 in which some of the exhaust gases collect to act as a gas cushion.

It is to be appreciated that mufflers, in order to be most efficient, must be varied in size, shape, etc., for various engines because a muffler which

will operate efficiently with one engine will not operate efficiently with another. In the muffler shown in Fig. 1 two megaphone shaped members 11 are used. Such a construction has been found to be efficient for certain engines, but with other engines it has been found that three, or even more of the megaphone members 11 are desirable in order to obtain most efficient muffling. The use of the diffusing cone 17 is advantageous in connection with the megaphone shaped communicating members 11, but in some instances this diffusing cone can be dispensed with. Also the provision of a gas cushion chamber at the rear end of the muffler can, if desired, be dispensed with inasmuch as the present invention is centered around the use of the megaphone shaped passageways 11, with the transverse perforated baffle plate 14, and with, or without, either or both, the diffusing cone 17 and/or the inwardly extending pipe 23.

A modified arrangement of the interior baffle members is shown in Figure 3 wherein a transverse perforated baffle 14a having a diffusing cone 11a is disposed between the megaphone shaped passageways 11a. It will be understood that the number of megaphone members can be varied to meet various requirements, and also if it be found desirable, the number of the transverse perforated baffle plates 14a, may be varied.

Considering the manner in which the exhaust gases pass through a muffler, it will be understood that the gases upon leaving the engine have a very high velocity and that they travel through the muffler at a high rate of speed and often upon entering the muffler are not completely burned. Picture a charge or body of exhaust gas entering the muffler shown in Figure 1 through the inlet 3. The exhaust gases enter the fairly large front chamber 25 wherein the same may expand, then this charge, or rather a portion thereof, passes on through the tapering tube member 11. At this point the outer layers of gas come into contact with the gradually reducing walls of the megaphone member 11 so that the movement of the outer layers of the body of gas are interfered with and retarded, whereas, the central part or heart of the charge passes through the opening in the communicating member 11. Thus the outer layers of gas are broken away or scraped off the central layers.

The central parts of the charge of gas then pass into the chamber 26, and thence through another communicating member 11 wherein the same action takes place, to wit: a scraping off of the exterior layers while the innermost portion passes freely through the communicating tube. The inner portion of the charge then strikes the diffusing cone 17 which breaks up the same and deflects it towards the inner wall of the shell. Thus it will be seen that by passing the exhaust gases through a plurality of successively arranged tapered tubes that the exterior strata is more or less gradually removed, until finally the interior portion of the gas is caused to be deflected towards the shell and then the gases must pass through the apertures 16 in the numerously perforated baffle plate 14 into the gas cushion 21 at the rear of the muffler, on into the re-entrant pipe 23 and thence to the atmosphere through the outlet 4.

Referring now to Figure 4, the invention, in a modified form, is embodied in a muffler made up of a one-piece shell 30 which shell is rolled into shape and formed with a longitudinal welded seam. Within the shell are several transverse

plates 31, each having formed centrally therein a tapering tubular member 33 and which plates may be welded, as shown at 32, to the shell. Figure 6 shows the communicating tube 33 on plate 31 in shell 30 through which the exhaust gases pass and are acted upon in the manner described in connection with Figure 1. The inlet of this muffler is shown at 35, and the outlet at 36. Disposed near the inlet there is positioned a baffle plate 37 provided with a plurality of apertures 38, shown in Figure 5. This perforated plate causes an initial diffusing of the exhaust gases, whereupon they pass through several successively arranged tapering tubular openings 33. Immediately to the rear of the last tapering tubular opening there may be placed a plate 39, provided with a plurality of openings 40, and a conical diffusing cone 42 which aids in diffusing the heart or central portion of the exhaust gases.

In adapting the muffler, shown in Figure 4 to 20 engines of various sizes, types and characteristics, it is contemplated that the number of the tapering tubular members, as well as the transverse baffle plates, may be varied and the diffusing cone as shown may, or may not, be used. Further, it 25 is contemplated that the arrangement of baffle members shown herein may by modifications that are obvious, be embodied and used in either sectional or shell type mufflers.

The operation of this invention having been 30 hereinbefore explained, illustrated and described, with a considerable degree of particularity as to the constructional details of the devices shown herein, it is to be understood that the invention is not limited to these forms and arrangements 35 of the several parts which may be modified within a wide range without departing from the essence of the present invention, and, therefore only such limitations are to be placed thereupon as are imposed by the prior art or as specifically 40 set forth in the subjoined claims. The present construction and the description based thereupon is intended to be taken in a descriptive rather than a limiting sense.

Having thus described the invention and desiring to secure and protect the same by Letters 45 Patent of the United States, I claim:

1. In an exhaust gas muffler the combination of a shell, heads at the opposite ends having respectively an inlet and an outlet, transversely extending flat partition plates in said shell spaced from the heads and from each other and forming a plurality of chambers, each of the said plates having an aperture approximately half the diameter of the shell, a longitudinally extending 50 tubular member secured to each aforesaid plate within said aperture and tapering to be smaller at its end towards the outlet and a further baffle plate numerously perforated over its area and placed across the shell, and spaced from the nearest tubular member and from either head.

2. In a muffler having an inlet at one end and an exhaust at the other, a plurality of chambers for the progression of exhaust gases and megaphone-shaped members permitting communication between said chambers, whereby to permit the progression of said gases through said chambers, partitions having perforations for breaking up and segregating the exhaust gases and a pipe extending into said muffler at the exhaust end to 65 form a gas cushion in said muffler to aid in deadening the sound of the exhaust gases before they reach the atmosphere.

3. In a muffler, having an inlet at one end and an exhaust at the other, a plurality of cups form- 70

5   ing chambers for the progression of exhaust gases, said cups having bottom surfaces, megaphone-shaped members fastened to said bottom surfaces for permitting communication with said chambers, whereby to permit the progression of said gases through said chambers, partitions having perforations for breaking up and segregating the exhaust gases and a pipe projecting into certain of said chambers at the exhaust end whereby 10 to form a pocket adapted to aid in deadening the sound of the exhaust gases before they reach the atmosphere.

4. In an exhaust gas muffler the combination of a shell, heads at the opposite ends having re-

spectively an inlet and an outlet, transversely extending flat partition plates in said shell spaced from the heads and from each other and forming a plurality of chambers, each of the said plates having an aperture of a substantial area, a longitudinally extending tubular member secured to each aforesaid plate within said aperture and tapering to be smaller at its free end pointed towards the outlet, a further baffle plate numerously perforated over its area placed across the shell, spaced from the nearest tubular member and either head, and a pipe extending into said muffler at the exhaust end and secured thereto. 5 10
